INVENTOR
JOHN R. IRWIN.

BY *John R. Irwin* FTTYS.

UNITED STATES PATENT OFFICE.

JOHN ROBERT IRWIN, OF COBOURG, ONTARIO, CANADA.

MEANS FOR TREATMENT OF PYORRHEA.

1,389,662.

Specification of Letters Patent. Patented Sept. 6, 1921.

Application filed April 6, 1920. Serial No. 371,730.

To all whom it may concern:

Be it known that I, Doctor JOHN ROBERT

IRWIN, a subject of the King of Great Britain, a resident of the town of Cobourg,

5 Province of Ontario, Dominion of Canada, have invented certain new and useful Improvements in Means for Treatment of Pyorrhea, of which the following is a specification.

10 This invention relates to improvements in a method and means for treating pyorrhea. It is well known in the dental profession that pyorrhea is the most prevalent and probably the most serious disease which 15 can affect the mouth and gums of a patient, and the result of this pyorrhea is so very serious that grave complications arise directly therefrom and in many cases prove fatal.

20 It will thus be seen that the disease is one which requires particular attention, and up to the present time any treatment of pyorrhea has only resulted in very indifferent success, and probably only a very 25 small percentage of cures have been obtained by older forms of treatment.

After a considerable amount of experimenting and research work, I have discovered that by treating this disease with 30 an electro-chemical treatment, vast majority of cases have resulted in apparent cure with the disappearance of the complications arising from the disease and the results have been such that I am of the opinion the cure 35 will be of a permanent nature.

Even very old and stubborn cases have yielded to this treatment with beneficial results to the patient.

So that the nature of my invention will 40 be properly understood reference is made to the accompanying drawings showing a form of my apparatus which is used in applying the treatment, and other objects of the invention will be readily understood as the 45 specification develops.

In the drawings:

Figure 1 is a perspective view of a device designed to be inserted in the mouth of a patient and carry an absorbent material designed to be saturated with a liquid, the 50 said device being provided with a terminal whereby an electric current may be passed through the apparatus to ionize the liquid and impregnate the gums of the patient 55 with the ions of the said solution.

Fig. 2 is a transverse section on the line 2—2 of Fig. 1.

Fig. 3 is a perspective view of a device designed to carry a piece of absorbent material saturated in a liquid, the material 60 being positioned adjacent to the gums on the inside of the teeth of the patient, the said device being provided with an electrical connection.

Fig. 4 is a transverse section on the line 65 4—4 of Fig. 3.

Like characters of reference refer to like parts in the several figures.

In carrying out my treatment of pyorrhea, I utilize an arcuate or curvilinear 70 member 10 in the form of a plate, the curvature being such that it will conform to the formation of the gums of the patient, and in one form of this plate, I provide inwardly extending grips or clamping members 11 75 adapted to engage and retain a roll of absorbent cotton 12 in position.

This absorbent cotton is saturated with a liquid which is electrically treated so that the liquid will become ionized, and the gums 80 of the patient impregnated with the said ions.

To facilitate passing a current of electricity through this liquid, I provide a terminal 13 which is secured to the front 85 of the plate 10, and is provided with an offset or hook shaped end 14 adapted to be connected by a suitable wire to one pole of a source of electric supply, and the terminal 13 is insulated by a sleeve 15 of rubber or 90 like material, so that the current will be advantageously utilized in ionizing the liquid with which the cotton has been saturated.

In Fig. 1 the apparatus shown is such 95 that it will be used on the outside of the gums of the patient.

In Fig. 3, the plate 10 is provided with the hooks or clamping members 11 which are directed outwardly, in this way differing 100 from the apparatus shown in Fig. 1, and the strip of absorbent cotton 12 extends around the outer face of the arcuate or curvilinear member 10. The plate 10 is provided in this case with a terminal 13 provided with a hook 105 end 14, the body of the terminal being insulated by a sleeve 15 of rubber or like material.

The apparatus shown in Fig. 3 is designed to be inserted wholly within the 110

mouth of the patient, so that the cotton 12 will be located in juxta-position to the gums on the inside of the teeth of the patient.

5 In utilizing this apparatus to carry out my method of treatment of pyorrhea I may say that the inner and outer portions of the gums may be treated simultaneously, but I prefer to treat them individually and 10 in separate operations.

It is immaterial when the inside and outside of the gums are being treated individually, whether the one is treated prior to the other.

15 In carrying out this operation the outside of the gums are to be treated, then the apparatus shown in Fig. 1 is used, and the apparatus is sterilized and a fresh piece of absorbent cotton 12 is prepared and thoroughly saturated in a solution, the cotton being then positioned in the clips or clamps 11, whereupon the curvilinear plate 10 is inserted in the mouth of the patient, the cotton 12 engaging with the outer portion of the 25 gums.

The hook end 14 of the terminal 13 is now attached to one pole of a source of electric supply, and the other pole of the source of electric supply will be attached in a suitable 30 manner to the hand of the patient, and when the electric circuit has been closed a current of the required strength will be passed through the plate 10, and, acting in an electrochemical manner on the solution with 35 which the cotton 12 has been saturated, will ionize the said solution and impregnate the gums of the patient with the said ions.

The duration of treatment will vary according to the stages of the disease, but I 40 have found that in most cases about fifteen minutes' treatment is sufficient in one operation.

After treating the outer gums a similar 45 operation will be performed on the inner gums but in this case the apparatus shown in Fig. 3 will be used.

The apparatus shown in Fig. 3 is thoroughly sterilized before use, and a fresh roll of absorbent cotton 12 is saturated in the 50 liquid and positioned on the clips or clamps 11, and the plate 10 is then placed in the mouth of the patient and drawn forward until the cotton 12 will be in contact with the inner gums of the patient's mouth.

The terminal 13 is now connected at the 55 hook end 14 to one pole of a source of electric supply, and an electric circuit is completed by connecting the hand of the patient to the other pole of the source of electric supply, whereupon current of a predetermined strength is passed through the plate 10, and after an electro-chemical action on the solution with which the cotton 12 has been saturated ionizes the said solution and impregnates the inner gums with the said 60 65 ions.

When the disease is old several such treatments will be required during certain intervals of time.

I have found with some patients whose 70 teeth can be freely moved that three or more treatments have effectively tightened the teeth in the sockets, and in such a way that they could not be moved with the fingers.

The other complications which arise from 75 the disease have also rapidly disappeared.

From this description it will be seen that I have invented an apparatus which can be utilized with my improved method of treatment of the disease of pyorrhea, and in 80 which very beneficial results have been obtained.

As many changes could be made in the above construction and many widely different embodiments of my invention within the 85 scope of the claim, constructed without departing from the spirit or scope thereof, it is intended that all matter contained in the accompanying specification and drawings shall be interpreted as illustrative and not in 90 a limiting sense.

What I claim as my invention is:

The apparatus used in the treatment of pyorrhea comprising an arcuate member designed to be inserted in the mouth and to 95 coincide with the gums, a solution retaining member carried by the arcuate member and adjacent to the gums, the said arcuate member being adapted to be connected to a source of electrical supply connected to the arcuate 100 member whereby a current of electricity is passed through the arcuate member to ionize the solution, and impregnate all the gums simultaneously with the solution.

In witness whereof I have hereunto set my 105 hand.

JOHN ROBERT IRWIN
